UNITED STATES PATENT OFFICE

JOHN A. COFFMAN, OF SEDGWICK, KANSAS

DESIGN FOR NECKTIE

Application filed September 14, 1929. Serial No. 32,751. Term of patent 3½ years.

To all whom it may concern:

Be it known that I, JOHN A. COFFMAN, a citizen of the United States of America, residing at Sedgwick, in the county of Harvey and State of Kansas, have invented a new, original, and ornamental Design for Neckties, of which the following is the specification, reference being had to the accompanying drawings, forming a part thereof.

I claim:

The ornamental design for necktie as shown.

In testimony whereof I affix my signature.

JOHN A. COFFMAN.
